UNITED STATES PATENT OFFICE.

HERBERT AUSTIN, OF BROMSGROVE, ENGLAND.

CARBURETER.

1,085,003.

Specification of Letters Patent. Patented Jan. 20, 1914.

Application filed July 25, 1913. Serial No. 781,458.

To all whom it may concern:

Be it known that I, HERBERT AUSTIN, a subject of the King of Great Britain, and residing at Bromsgrove, in the county of Worcester, England, engineer, have invented 5 certain new and useful Improvements in or Relating to Carbureters for Internal-Combustion Engines, of which the following is a specification.

10 This invention relates to the type of carbureter in which a cylindrical valve, within which the jet nozzle is situated, is utilized as a throttle for the combustible mixture to the engine and as a control device for the jet 15 nozzle; and has for its main object, improvements whereby the best results may be obtained as to the richness of the mixture for variations in the throttle opening, and whereby independent adjustment of a control device for the nozzle may be effected 20 without dismantling any portion of the apparatus.

In order that the invention may be clearly understood, I will now describe a convenient 25 application thereof by reference to the drawings herewith, of which:

Figure 1 is a vertical section, taken in the plane indicated by line $\alpha\alpha$ of Fig. 2, of a carbureter to which the invention is applied. Fig. 2 is a vertical section, taken in the plane indicated by line $\gamma\gamma$ of Fig. 1, except that the float-feed apparatus is shown simply in elevation, and; Fig. 3 is a detached view of a detail of the apparatus.

30 The carbureter body $\mathbf{A}$ is formed with a cylindrical case $\mathbf{A}'$, having a horizontal axis, within which is a hollow cylindrical valve $\mathbf{B}$. Both the case $\mathbf{A}'$ and the valve $\mathbf{B}$ are originally formed open at the sides thereof which 35 in use will be toward the float-feed apparatus $\mathbf{C}$. The outer side b of the valve $\mathbf{B}$ is formed closed, and the outer side of the case $\mathbf{A}'$ is formed with a flange a against which the outer side of the valve $\mathbf{B}$ abuts. The 40 valve $\mathbf{B}$ is formed or provided with a spindle b' which passes through the opening of the case $\mathbf{A}'$ which is surrounded by the flange a thereof. A plug $\mathbf{D}$, which is made rigid with the float-feed case, such as by screwing 45 it upon a nipple c of such case, is passed sidewise into the valve $\mathbf{B}$. The valve is just a turning fit between the outer surface of the plug $\mathbf{D}$ and the inner surface of the case $\mathbf{A}'$, and a shoulder d of the plug, coming 50 against the open end of the valve, maintains the valve in position endwise, and a

shoulder d' of the plug abuts against the corresponding end of the case $\mathbf{A}'$ and is tightened thereagainst in any convenient manner, such as by bolts passing through lugs of the case and of the plug. A passage d^2 of circular transverse section, and of large area, is formed transversely through the middle of the plug $\mathbf{D}$, being, conveniently, somewhat smaller in diameter at its middle than at its ends and enlarging gradually from its middle to the ends, as clearly shown by Fig. 1, and when the valve is in its fully open position, as shown, ports b^2 b^3 of the valve register, respectively, with the inlet and outlet ends of the passage d^2 , and put such ends in full communication with corresponding openings of the case $\mathbf{A}'$ for the passage of inlet air and of combustible mixture to the engine, respectively. The liquid fuel nozzle $\mathbf{E}$ stands up from the bottom of the middle of the passage d^2 to about half the height of the passage, and liquid fuel from the float-feed chamber passes to the nozzle through the nipple c and through the passage d^4 of the plug $\mathbf{D}$. Within the portion of the plug $\mathbf{D}$ which is above the passage d^2 , therethrough is fitted to be slidably vertically a slider $\mathbf{F}$, and between a shoulder d^5 of the plug and a shoulder f of the slider is inserted a spiral spring f' which tends to constantly press the outer end of the slider against the inner surface of the valve $\mathbf{B}$. A pin $\mathbf{G}$, formed at its lower end as a needle-valve g , is screwed axially through the slider $\mathbf{F}$, and this pin has a common axis with the liquid fuel nozzle $\mathbf{E}$. The pin $\mathbf{G}$ passes also through a plug $\mathbf{H}$ which closes an opening through the top of the case $\mathbf{A}'$ through which the pin passes, and the pin is formed at its outer end with a milled head g' for convenience in manipulating it. The pin $\mathbf{G}$ passes through a slot b^4 which is formed through the wall of the valve $\mathbf{B}$ to allow of the valve being turned notwithstanding the passage therethrough of the pin $\mathbf{G}$.

The inner surface b^5 of the portion of the valve $\mathbf{B}$ through which the slot b^4 is formed, is shaped, as shown, so that as the valve is turned in the direction of the arrow (Fig. 1), namely in the direction to cut off mixture from the engine, this surface, pressing against a correspondingly-shaped surface of the outer end of the slider $\mathbf{F}$, will move the slider inward, and thereby cause the needle-valve g to close, or restrict the effective area

- 2 of; the opening of the nozzle E; and this surface b^5 is so shaped as to insure that for any degree to which the valve has been turned, the opening of the nozzle E will be such as to give the best result in working. Preferably, the portion of the slider against which the surface b^6 of the valve bears is made considerably narrower than the main diameter of the slider, as shown by Fig. 2.
- 5 10 The openings b^2 and b^3 through the wall of the valve B are so formed that as the valve is turned from its position shown by Fig. 1, in the direction of the arrow (Fig. 1), both the passage-way for mixture to the engine and the passage-way for inlet air will be restricted, and, as the nozzle E is at right-angles to the axis of the valve, the turning of the valve tends to insure a flow of air through the passage d^2 in a slanting direction upward from the air inlet to the mixture outlet, crossing the middle of the passage-way at about the level of the top of the nozzle, which constitutes an incidental advantage of the use of the invention.
- 15 20 25 The cam-shaped surface b^5 of the interior of the valve B, is conveniently formed by cutting a slot through the wall of the valve and forming rabbets b^6 at the ends of the slot, and then letting into this slot a strip of metal b^7 , which has the required cam surface formed at its inner face, with the ends of the strip fitted down within the rabbets, and fixing the strip to the valve by screws b^8 . The strip, with its screws, is shown detached by Fig. 3, which represents it as seen looking down thereupon when in the position shown by Fig. 1. The slot b^4 , to clear the pin G, is formed through the strip.
- 30 35 Having fully described my invention, what I claim and desire to secure by Letters Patent, is:—
1. In a carbureter for an internal combustion engine, a fixed plug, a transverse passage through such plug, a fuel nozzle situated within the plug, a cylindrical throttle valve which has a turning fit around the plug, openings through the valve, a fixed cylindrical case within which the valve has a turning fit, an inlet and an outlet opening through the wall of the case, a fuel control device which is carried by the plug, and means whereby as the valve is turned in a direction to throttle the mixture it operates the control device, substantially as and for the purposes set forth.

2. In a carbureter for an internal combustion engine, a fixed plug having a horizontal axis, a transverse passage through such plug, a fuel nozzle situated within and carried by the plug, a fuel passage formed in the substance of the plug and communicating with the nozzle, a cylindrical throttle valve which has a turning fit around the plug, openings through the valve, a fixed cylindrical case within which the valve has a turning fit, an inlet and an outlet opening through the wall of the case, a device slidably fitted within the plug, a fuel control valve carried by such device, a cam-shaped surface of the throttle valve adapted to contact with the outer end of said device and move it inward, and a spring against the force of which the device is moved inward by the throttle valve, substantially as and for the purposes set forth.
3. In a carbureter for an internal combustion engine, a fixed plug, a transverse passage through such plug, a fuel nozzle situated within the plug, a cylindrical throttle valve which is closed at one end and passed endwise over the plug and has itself a turning fit around the plug, openings through the valve, a fixed cylindrical case within which the valve has a turning fit, an inlet and an outlet opening through the wall of the case, a fuel control device which is carried by the plug, and means whereby as the valve is turned in a direction to throttle the mixture it operates the control device, substantially as and for the purposes set forth.
4. In a carbureter for an internal combustion engine, a float-feed apparatus, a fixed plug which is rigid with the float valve case, a transverse passage through such plug, a fuel nozzle situated within the plug, a cylindrical throttle valve which has a turning fit around the plug, openings through the valve, a fixed cylindrical case within which the valve has a turning fit, an inlet and an outlet opening through the wall of the case, a fuel control device which is carried by the plug, and means whereby as the valve is turned in a direction to throttle the mixture it operates the control device, substantially as and for the purposes set forth.
5. In a carbureter for an internal combustion engine, a fixed plug, a transverse passage through such plug, a fuel nozzle situated within the plug, a cylindrical throttle valve which has a turning fit around the plug, openings through the valve, a fixed cylindrical case within which the valve has a turning fit, an inlet and an outlet opening through the wall of the case, a device slidably fitted within the plug, a fuel control valve carried by such device, a cam-shaped surface of the throttle valve adapted to contact with the outer end of said device and move it inward, and a spring against the force of which the device is moved inward by the throttle valve, substantially as and for the purposes set forth.
6. In a carbureter for an internal combustion engine, a fixed plug, a transverse passage through such plug, a fuel nozzle situated within the plug, a cylindrical throttle valve which has a turning fit around the plug, openings through the valve, a fixed cylindrical case within which the valve has a turning fit, an inlet and an outlet opening through the wall of the case, a device slidably fitted within the plug, a fuel control valve on the inner end of a pin which is

screwed through said device and the outer end of which is exposed and adapted to be readily turned, and means whereby as the throttle valve is turned in a direction to throttle the mixture it operates said device and consequently also said fuel control valve, substantially as and for the purposes set forth.

7. In a carbureter for an internal combustion engine, a fixed plug having a horizontal axis, a substantially horizontal transverse passage through such plug, a fuel nozzle standing up within the middle of the passage through the plug to about half the height of such passage, a cylindrical throttle valve which has a turning fit around the plug, openings through the valve situated in such po-

sitions in relation to one another that as the valve is turned in a direction to throttle the mixture the ends of the passage are gradually closed one of them from the lower side thereof and the other from the upper side thereof, with the result that the air flowing through the passage passes in an inclined direction across the middle of the passage at 20 about the level of the top of the nozzle, substantially as and for the purposes set forth.

In witness whereof I have hereunto signed my name this 16th day of July 1913 in the presence of two subscribing witnesses.

HERBERT AUSTIN.
